(57) **CLAIM**

The ornamental design for a tool holder for T-shaped tools, as shown and described.

DESCRIPTION

FIG. 1 is a right and front perspective view of a tool holder for T-shaped tools showing our new design with a rigid body and a resilient retaining member;

FIG. 2 is left and rear perspective view thereof;

FIG. 3 is a left-side elevational view thereof;

FIG. 4 is a right-side elevational view thereof;

FIG. 5 is a front elevational view thereof;

FIG. 6 is a rear elevational view thereof;

FIG. 7 is a top plan view thereof;

FIG. 8 is bottom plan view thereof; and,

FIG. 9 is a right and front perspective view of the tool holder for T-shaped tools shown in an alternate position of use holding a T-shaped tool.

wherein objects illustrated in broken lines form no part of the claimed design.

1 Claim, 4 Drawing Sheets
